JOINT FOR ROAD CONSTRUCTION

Louis B. Johnson, Baltimore, Md.

Application August 4, 1939, Serial No. 288,420

2 Claims. (Cl. 94—17)

My present invention relates to joints for roadways and more particularly to such a joint adapted to be positioned above the sub-grade of the roadway to produce a fault or crack in the concrete of the roadway.

One of the primary objects of the invention is the formation of a joint in the form of interconnected units whereby each unit when placed on the sub-grade of the roadway will position a joint-forming strip a predetermined distance above the roadway.

Yet another aim is the construction of a joint having a plurality of spaced transversely extending hook-shaped supports for the joint strip whereby said supports will not only position the joint strip a predetermined distance above the roadway but will also function as reinforcement for the concrete and additionally tend to tie together the sections constituting the roadway.

Still a further purpose of the invention is the formation of a joint including a flexible joint strip whereby the joint finds application in the building of curves in the roadway.

The above and other aims and objects will be apparent from the detailed description herein-after appearing when taken in conjunction with the appended drawing forming a part hereof to which reference is now made and in which—

Fig. 1 is a perspective view of a road joint unit embodying the invention and showing a joint-forming strip and its supports.

Fig. 2 is a sectional view through a portion of the roadway showing the joint unit positioned on the roadway.

Fig. 3 is a sectional view taken on line 3—3 of Fig. 2.

Fig. 4 is a plan view showing how the joint strip may be flexed for use in building a curved section of roadway.

As is well known, in the building of concrete roadways of full width construction as distinguished from the lane-at-a-time method, a center line joint should always be provided. It has been found that a very efficient joint of the type indicated is produced by forming a fault or crack in a predetermined position in the road. The instant invention is concerned with a unit adapted to be placed on the sub-grade of the roadway preferably to form a longitudinal joint in the road when a number of units are joined end to end.

Referring now to the drawing wherein a preferred embodiment of the invention is illustrated, the reference character U represents a joint unit in its entirety formed of proper gauge steel or

the like, said unit being characterized by a thin flexible steel strip 10 of any preferred width. In practice, strip which is about one-eighth inch thick, two inches wide and five feet long has been found to be highly practical. The strip 10 is adapted to be mounted in a vertical plane normal to the sub-grade S of a roadway R within the concrete C thereof. To support the joint strip 10 in the manner indicated a pair of similar 10 longitudinally-spaced transverse steel supports 11 are employed, the distance between the supports being preferably about two-and-a-half feet. Each support 11 is about one-half inch thick, and is characterized by a horizontal section 12 terminating in similar inwardly curved end sections 13, 13a. It will be noted that the bottom edge 14 of strip 10 rests on the upper surfaces of each horizontal section 12 centrally of its curved ends 13, 13a, and is welded thereto as indicated at 15. A plate 16 of an approximate size of two inches square is welded as at 17 to the bottom edge of each curved end 13, 13a. The plates 16 are adapted to rest on the subgrade of the roadway R and the strip 10 will be held by supports 13, 13a above the subgrade a predetermined distance to form a longitudinal joint between road sections 18 and 19 in a manner to be shortly described. Welded as at 20 to each horizontal section 12 of supports 11 and adjacent flexible strip 10 is a washer 21 adapted to receive a pin 22' or the like therethrough. One end of each strip 10 carries a sleeve or the like 22 for receiving the free end 23 of the strip 10 of an adjacent unit U, see Fig. 3.

25 In forming a longitudinal joint in the roadway a unit U is positioned on the sub-grade S of the roadway in the manner illustrated in Figs. 2 and 3, and each unit is held in place against displacement by means of pins 22' passing through the washers 21 welded to each unit. It will be noted that the flexible strip 10 will now be held a predetermined distance above the sub-grade S and with the dimensions of the unit given as illustrative, this distance will be about four inches. Successive units U are also placed on the sub-grade S in end to end relationship, the units being held in alignment by means of the sleeves 22. After the units are in place, concrete C is poured on the sub-grade over the units to form road sections 30 and 31. When the concrete hardens irregular cracks 30 and 31 are formed respectively below and above the strip 10 and substantially in alignment therewith. These cracks 30 and 31 constitute an efficient joint as will be understood by those skilled in the art. By means of the

curved ends 13, 13a not only is the strip positioned above the sub-grade S, but the concrete C is reinforced and the road sections 18 and 19 tied to each other. By making the strip 10 flexible it is possible to provide for a curve in the roadway, the unit U being flexed as shown in Fig. 4 to bring the supports 11 in intersecting planes instead of parallel planes when the strip 10 is in normal or unflexed condition. In some instances it is not desired to have the uniting function of the two curved ends 13, 13a of a support 11 and in such case one of the curved ends 13 or 13a is eliminated by making same a continuation of horizontal portion 12 and in the same plane therewith. The uncurved end may then be supported by various means until the concrete is poured and the supports will then be removed. The crack 31 may be filled with material such as tar or the like up to the level of the sections 18 and 19.

While the invention has been described in detail it will be apparent that various changes may be made in the specific embodiment thereof illustrated. Thus, the dimensions given are to be considered as purely illustrative and although the different elements of the units are described as welded together they may be fixed to one another by other means and in other ways.

It will also be appreciated that the rigid unit described eliminates the assembling by hand of constituent parts which has been the practice heretofor. Also, it will be understood that all the units will remain in perfect alignment at all times, particularly during construction of the roadway and will produce a true perfectly aligned joint. Another great advantage is that the unit forms a much better bond of the concrete to the supports or tie bars due to the curved ends there-

of which is not possible with the use of straight tie bars and supporting means therefor.

It will also be evident that the units are easily handled and readily placed in operative position on the roadway thus constituting a material saving in labor and costs all of which are highly desirable. All of the above features provide a unit with more bond which is preferred from an engineering standpoint.

What I claim and desire to secure by Letters Patent is:

1. A joint for roadways comprising a flexible strip producing a joint in the roadway, means for supporting said strip, said means comprising independent spaced rods fixed to and extending transversely of said strip, each rod comprising a horizontal portion to which the strip is secured, said horizontal portion terminating in inwardly curved and downwardly extending ends, a horizontal plate secured to each inwardly curved portion forming an extension thereof to rest flatly on the sub-grade of the roadway, and means for holding the joint in fixed position on the sub-grade.
2. A joint for roadways comprising a flexible strip producing a joint in the roadway, means for supporting said strip, said means comprising independent spaced rods fixed to and extending transversely of said strip, each rod comprising a horizontal portion to which the strip is secured, said horizontal portion terminating in inwardly curved and downwardly extending ends, a plate secured to each end to rest flatly on the sub-grade of the roadway, and means comprising washers secured to the rods and removable pins passing through the washers for holding the joint in fixed position on the sub-grade.

LOUIS B. JOHNSON.
